CARTON FOR RADIO TUBES

Christian Mowry Knaur, Williamsport, Pa.

Application June 21, 1935, Serial No. 27,808

9 Claims. (Cl. 229—39)

This invention relates to certain new and useful improvements in cartons for radio tubes and the like, the object being to provide a carton with means for resiliently supporting a radio tube therein in such a manner that it can move longitudinally in order to project one end thereof outwardly in order to test the tube and yet the tube is permanently locked within the carton so that it cannot be removed without destroying the carton, thereby preventing "bootlegging" of an inferior product and the unauthorized packing of such product.

Another object of my invention is to provide a carton which is formed from a single blank to provide a tubular casing having integral end closures provided with self-locking tongues and integral partitions for supporting the radio tube whereby the carton can be manufactured cheaply, the partitions being so constructed and connected to one wall of the casing by flaps that resilient means is provided for supporting the tube, the partitions being adapted to be bowed in order to resiliently support the tube whereby the tube will have a tendency to return to its original position after the end has been forced outwardly to test the same.

Another object of my invention is to provide a novel construction for locking the end closures after the tube has been placed in position within the container without the use of glue or separable fastening means, whereby the cost of manufacturing the container is greatly reduced and a positive lock is provided for the end closures to prevent the tube from being removed without destroying the container.

Other and further objects and advantages of the invention will be hereinafter set forth and the novel features thereof defined by the appended claims.

In the drawings,

Figure 1 is a perspective view of a container constructed in accordance with my invention;

Figure 2 is a longitudinal section showing the radio tube in dotted lines in its normal position;

Figure 3 is an enlarged longitudinal section showing the radio tube extended in position to be tested;

Figure 4 is a section on line 4—4 of Figure 2;

Figure 5 is a detail perspective view showing the locking tongue before it has been inserted within the slot of the wall of the container;

Figure 6 is a detail perspective view showing the locking flaps of the tongue bent in position to be forced through the slot in the wall of the container; and

Figure 7 is a plan view of the blank from which the carton is formed.

In carrying out my invention, I form the complete carton from a single blank of cardboard or other suitable material, which comprises a tubular casing formed of side walls 1, 2, 3 and 4, the wall 4 being provided with a flap 5 which is adapted to be secured to the inner face of the wall 1 by any suitable adhesive material, the flap being formed by a score as shown in dotted lines. Formed integral with the wall 3 of the tubular container at each end are end closures 6 and 7 which are scored as shown to provide side flaps 6' and 7' and locking tongues 8 and 9, the locking tongues 8 and 9 being scored as shown by dotted lines to provide resilient locking ears 8' and 9', forming substantially T-shaped heads, these locking tongues and ears being adapted to be bent into the position shown in Figure 6 and forced through slots 10 formed in the wall 1 of the tubular casing in order to lock the closures in closed position as will be hereinafter more fully described.

The end closures 6 and 7 are provided with opening 6² and 7², opening 6² being for the purpose of allowing a finger or thumb to be inserted in order to force, as for example, a radio tube 11 outwardly through the opening 7² in order to allow it to be tested as clearly shown in Figure 3.

Formed integral with the ends of the wall 1 of the tubular container are tube supporting members 12 and 13 which are scored on the dotted lines to produce partitions 14 and 15, connecting flaps 16, 17 and 17' and guide flaps 18 and 19.

The tubular container formed by the side walls 1, 2, 3 and 4 is preferably rectangular in shape and can be formed of any suitable material, such as pasteboard and the like. After the flap 5 has been cemented to the wall 1, the tube supporting members 12 and 13 are forced inwardly through the open ends of the tubular container into the position shown in Figure 2 and the size of the partitions 14 and 15 is such that they are bowed as clearly shown, it, of course, being understood that the radio tube 11 is placed in position within the carton within the partition 15 before the partition 14 is forced into position. When the partition 14 is forced into position, the end of the tube extends into the opening 14', the other end of the tube being seated in the opening 15' of the partition 15 and as both of these partitions are of a greater size than the inner size of the container, they bow when placed in position therein so as to resiliently sup-

port the tube 11 whereby when the tube is in its normal position as shown in Figure 2 and is forced outwardly to test the same into the position shown in Figure 3, the partition bends so that the bow is in the opposite direction and as the cardboard is flexible, it has the tendency to return to its original position when pressure is removed from the same so as to return the radio tube into its normal position.

10. The connecting flaps 16, 16', 17 and 17' of the partitions 14 and 15 assume the position shown in Figures 2 and 3 when forced into position within the container in order to provide pockets 20 and 21 to protect the locking tongues 8 and 15 9 when in locked position, whereby it is impossible to insert an instrument of any kind into the carton and manipulate the ears 8' and 9' of the locking tongues 8 and 9 in order to release the same and to allow the closure members to be opened whereby a positive lock is provided which, when once inserted into locked position, closes the ends of the carton and permanently locks the radio tube therein so that it is impossible to remove the same without destroying the carton.

25. Assuming that the radio tube has been placed in position within the carton within the resilient supporting means, the ears 8' of the locking tongue 8, as for example, are bent back upon the tongue into the position shown in Figure 6 and 30 forced through one of the openings 10 and as the material from which the tongue is formed is flexible, the ears of the tongues spread outwardly after passing through the opening so as to positively and permanently lock the closure 35 in closed position. It is, of course, understood that the opposite end closure is secured in a like manner and the radio tube will now be packed in a carton so as to thoroughly protect the same in shipment and yet allow the same to move 40 therein so that one end can be projected outwardly in order to test the same and as the partitions are flexible, it not only resiliently supports the radio tube, but has the tendency to return the tube to its normal position within the 45 container after being forced outwardly to test the same.

While in the drawings and specification I have shown and described a carbon especially designed for the merchandising of radio tubes, it 50 is, of course, understood that the same can be used for merchandising electric light bulbs or any other objects which are generally tested to determine their condition prior to sale.

From the foregoing description it will be seen 55 that I have provided a carton with resilient partitions resiliently supported within the container for supporting a radio tube resiliently to enable one end of the tube to be forced out of the container in order to allow the same to be tested 60 and when released, will return to its normal position by the resiliency of the supporting means and partition.

What I claim is:

1. A container of the kind described comprising an outer casing, resilient apertured partitions 65 resiliently supported in said casing for movably supporting a radio tube within said casing, said partitions forming pockets, openings formed in said casing aligned with said pockets, apertured 70 members provided with permanently locking tongues cooperating with said openings for closing the ends of said container and for locking the radio tube within said container.

2. A carton for radio tubes and the like comprising a tubular oblong body having formed in-

tegral therewith apertured end closures provided with integral locking tongues cooperating with said slots formed in a wall of the body for permanently locking said closures in closed position, partitions formed integral with said body 5 provided with openings to receive a tube, said partitions being bowed within said body to resiliently support a tube within said body and to allow said tube to move longitudinally a predetermined distance therein, portions of said 10 partitions forming guards for the locking means of said closures.

3. A carton of the kind described comprising a tubular body having formed integral therewith tube supporting members provided with 15 apertured partitions to receive a tube, said tube supporting means providing pockets, the wall of said tubular body being provided with slots communicating with said pockets and apertured end closure members formed integral with said 20 body provided with resilient locking tongues adapted to be forced through said openings into said pockets for permanently locking said closure members in closed position.

4. A carton for radio tubes comprising a rectangular casing having spaced openings formed in one wall thereof, said wall having formed integral with the ends thereof tube supporting members scored to provide partitions having apertures to receive a tube, said partitions being 30 bowed within said rectangular casing for resiliently supporting a tube therein, end closures formed integral with another wall of said casing provided with apertures and scored to provide flaps and locking tongues, the locking tongues 35 being provided with resilient ears adapted to be forced through the slots of said casing for permanently and positively locking said end closures in closed position, the tube supporting members forming guards for the locking tongues of 40 said closures.

5. A carton of the kind described comprising a rectangular hollow body formed of side walls, one of which is provided with a flap for securing the same to another wall to form a rectangular body, said body having formed integral therewith resilient tube supporting members for movably supporting a tube within said body, said body having apertured end closures provided with resilient locking tongues cooperating with 50 slots formed in said body for permanently locking said end closures in closed position, the tube supporting members forming guards for the locking tongues of said end closures.

6. A carton as herein shown and described 55 having integral resilient tube supporting means and integral end closures provided with resilient locking tongues for permanently locking said closures in closed position, the tube supporting means forming guards for preventing the locking 60 tongues from being removed.

7. A carton of the kind described comprising a rectangular tubular body having an opening formed in one wall thereof adjacent its ends, flaps formed integral with said wall carrying 65 apertured partitions for movably supporting a tube within the body, said flaps being provided with extensions forming pockets within the body over said slots to provide guards therefor, and end closures formed integral with one wall of 70 said body having locking tongues provided with portions adapted to be bent back upon themselves to allow said tongues to be forced through said slots into said pockets in order to allow said bent portions to expand for permanently

locking said closures in closed position across the ends of said body.

8. A carton of the kind described comprising a tubular body, tube supporting members movably mounted in said body for movably supporting a tube therein, said tube supporting members being provided with extensions bent to form pockets to provide guards, said body having openings registering with said pockets, apertured 10 end closures for said body and locking tongues carried by said end closures provided with resilient ears adapted to be bent back upon themselves and forced through said openings into said pockets to allow said resilient ears to ex-

pand for permanently locking said end closure members in closed position.

9. A carton of the kind described comprising a tubular body having openings formed in the wall thereof, pockets formed in said body over 5 said openings to provide guards therefor, tube supporting members mounted in said body for supporting a tube therein and apertured end closures for said body having resilient locking tongues adapted to be forced through said openings into said pockets for permanently locking said end closures in closed position over the ends of said body. 10

CHRISTIAN MOWRY KNAUR.
